UNITED STATES PATENT OFFICE.

CHARLES E. HOWARD, OF CHICAGO, ILLINOIS.

EQUALIZER FOR FURNITURE-DRAWERS.

SPECIFICATION forming part of Letters Patent No. 591,134, dated October 5, 1897.

Application filed August 28, 1896. Serial No. 604,155. (No model.)

To all whom it may concern:

Be it known that I, CHARLES E. HOWARD, a citizen of the United States, residing at Chicago, in the county of Cook and State of Illinois, have invented certain new and useful Improvements in Equalizers or Regulators for Furniture-Drawers, of which the following is a specification.

This invention relates to improvements in a device to be used for regulating and equalizing the movements of the drawers in dressing-cases, desks, bureaus, and other pieces of furniture; and it consists in certain peculiarities of the construction, novel arrangement, and operation of the parts thereof, as will be hereinafter more fully set forth and specifically claimed.

In pieces of furniture of the ordinary or general construction the drawers thereof frequently become jammed in their withdrawal, removal, or insertion by reason of the fact that one portion or end of the drawer is withdrawn or inserted unevenly or more rapidly than the other end or portion and causes great annoyance and inconvenience.

It is therefore the objects of my invention, first, to provide a device for equalizing and regulating the removal or insertion of furniture-drawers which shall be simple and inexpensive in construction, strong, durable, and effective in operation, and, second, such a device which shall be so applied as to be ordinarily invisible and will prevent the drawer being jammed or becoming fixed in its guides, 35 way whether or not the power of removing it shall be applied equally on its handles.

In order to enable others skilled in the art to which my invention pertains to make and use the same, I will now proceed to describe it, referring to the accompanying drawings, in which—

Figure 1 is a bottom plan view of a piece of furniture with the drawer therein, showing my equalizer in position and ready for use; and Fig. 2 is an enlarged cross-sectional view taken on line 2 2 of Fig. 1.

Similar letters refer to like parts throughout both views of the drawings.

A represents the main frame or outer portion of the piece of furniture, which is provided, as usual, with one or more openings a

in its front part for the reception and operation of the drawer or drawers B. Just below and near each end of the opening a for the drawer B and extending horizontally across the main frame or casing A is secured a cleat C, on which the ends or sides of the drawer rest and slide in its movements. To the front portion and on the adjacent surfaces of each of these cleats is secured a bearing-bracket D for the shaft or rod E, on each end of which is rigidly secured a cogged gear or pinion E' to mesh with the toothed rack-bars F, which are secured to the bottom of the drawer near its ends or sides. The bearing-brackets D are formed or provided with an inwardly extending and curved flange D', which encompasses the gear E' or pinion and prevents clothing and other articles which may be in the drawer beneath from becoming entangled therewith.

In order to adjust the bearings of the shaft or rod E so that the pinions or gears thereon will properly mesh with the rack-bars F, I form the bearing-pieces D with an opening at their rear ends for a screw d to pivotally secure them to the cleats and between said openings and the bearing-points for the shaft with a slot d', through which another screw d² may be inserted to secure the bracket at the desired position. It is apparent by employing this construction that the bracket, being pivoted on the screw d, may be raised or lowered at its other end to any desired position and there firmly held by tightening the screw d² in the slot d' therefor. The drawers are usually provided with handles b on their front portions for the convenience of their removal and insertion, and by using my equalizer it is obvious that the drawer will be caused to move uniformly and evenly at each side or end, thus preventing it becoming fixed or jammed in the casing or main frame of the article of furniture.

Having thus fully described my invention, what I claim as new, and desire to secure by Letters Patent, is—

The combination with the main frame, having an opening for the drawer, of a bearing-bracket pivotally and adjustably secured to each side of the main frame below said opening, each of said brackets having a curved

flange on the adjacent surfaces, a shaft or rod having its bearings in said brackets, a cogged gear or pinion rigidly fixed on each end of said shaft or rod, and adapted to operate within the curved flange of the brackets, and a rack-bar secured to the bottom of the drawer at each side or end thereof and

adapted to mesh with the cogged gears or pinions, substantially as described.

CHARLES E. HOWARD.
